UNITED STATES PATENT OFFICE.

FRED R. REED, OF DETROIT, MICHIGAN, ASSIGNOR OF ONE-HALF TO LOUIS J. MCKENNEY,
OF DETROIT, MICHIGAN.

VEHICLE-LAMP.

1,266,157.

Specification of Letters Patent. Patented May 14, 1918.

Application filed December 15, 1916. Serial No. 137,201.

To all whom it may concern:

Be it known that I, FRED R. REED, a citizen of the United States of America, residing at Detroit, in the county of Wayne and State of Michigan, have invented certain new and useful Improvements in Vehicle-Lamps, of which the following is a specification, reference being had therein to the accompanying drawings.

10 The invention relates to vehicle lamps of the type employed as headlights, and it is the object of the invention to obtain a construction for projecting a powerful light so as to illuminate the road and at the same time to limit the angle of the intense light rays to approximately a horizontal line. It is a further object to obtain a construction which is applicable to lamps of standard lines and which also provides for a moderate 15 illumination of greater angle.

In the drawings:

Figure 1 is a perspective view, showing the forward portion of a motor vehicle with my improved lamp applied thereto;

25 Fig. 2 is a diagrammatic vertical central section through the lamp;

Fig. 3 is a front elevation thereof.

In the present state of the art the standard construction of lamp is one having a 30 casing of parabolic form, containing a reflector of similar form with the lamp arranged at the focal point. It is also common to provide such lamps with an auxiliary 35 light of lesser power and arranged at a point out of focus. The focused light when used is projected through an angle which not only illuminates the road but forms an objectionable glare above the lamp level; while, on the other hand, the auxiliary lamp is too 40 feeble to produce satisfactory road illumination. With the present invention I have arranged within a lamp casing of standard 45 lines, a reflecting shield which throws a concentrated light upon the road but limits the angle to the horizontal. I have also arranged this shield so as not to interfere with the auxiliary light or to limit the angle of the rays therefrom.

In detail, A is the parabolic casing of the 50 lamp, which may represent the inner lining or reflector of standard construction. B is the lamp proper, which is arranged at the focal point of said casing, and C is the auxiliary lamp, which as shown is arranged 55 in the upper forward portion of the casing.

D is the line representing the plane of the glass front. E is a conical reflector within the casing A, having its axis substantially coincident with the casing A and having its wall inclined at substantially a 45° angle 60 to said axis. F is a reflector arranged at an upward angle of less than 45°, preferably approximately 22½° from the horizontal and of a concave form. G is a combined shield and counter-reflector arranged at an angle 65 preferably of substantially 45°, and having its forward edge in the plane of the front D and the horizontal plane of the lamp B. The rear edge of this reflector intersects with the reflector F, as indicated by the 70 line H.

With the construction as described, all of the light from the lamp B will be projected below the horizontal plane, while the greatest concentration is in a downward direction 75 upon the road immediately in advance of the vehicle. On the other hand, the rays from the auxiliary lamp C are not so limited but may be dispersed through a much wider angle.

80 One advantage of my construction is that a concentrated light is thrown upon the path immediately in advance of the vehicle and at the same time light is projected forwardly below the horizontal plane for a considerable 85 distance. This gives the desired illumination and without any objectionable glare.

80 What I claim as my invention is:

1. A reflector for a vehicle lamp having a 90 parabolic casing and a lamp located substantially at the focus of said casing, said reflector being insertible within said casing and comprising a lower portion extending from the margin of the casing to a position in rear of the lamp, an upper portion connecting with the upper edge of said lower portion and forming an acute angle with the horizontal, and a reversely-inclined portion connecting with the forward and upper edge of said acute angle portion, said reversely inclined portion being in front of said acute angle portion and having its lower edge in substantially the horizontal plane of the lamp.

2. A reflector for a vehicle lamp having a 105 parabolic casing, a transparent face for said casing and a lamp located substantially at the focus of said casing, said reflector being insertible within said casing and having a continuous reflecting surface, comprising a 110

lower portion at substantially 45° to the horizontal and extending from the margin of the casing to a position in rear of the lamp, an upper portion at an angle of substantially 22° to the horizontal and a reversely-inclined portion in front of said upper portion and having its lower edge in substantially the horizontal plane of the lamp and adjacent to the transparent face 10 for the casing.

3. A reflector for a vehicle lamp, comprising a conical lower portion and an upper portion having front and rear members intersecting at an upward inclination, the lower edge of the front member being substantially in the horizontal plane of the axis of the conical member. 15

In testimony whereof I affix my signature.

FRED R. REED.
